US0D1088881S

(12) **United States Design Patent** (10) **Patent No.:** **US D1,088,881 S**
(45) **Date of Patent:** **** Aug. 19, 2025**

(54) **GLASS STORAGE JAR**

(71) Applicant: **Guangzhou Shengjiu Technology Co., Ltd.**, Guangzhou (CN)

(72) Inventor: **Shengpeng Wei**, Guangzhou (CN)

(73) Assignee: **Guangzhou Shengjiu Technology Co., Ltd.**, Guangzhou (CN)

(**) Term: **15 Years**

(21) Appl. No.: **29/903,579**

(22) Filed: **Sep. 26, 2023**

(30) **Foreign Application Priority Data**

Apr. 26, 2023 (CN) 202330237335.5

(51) **LOC (15) Cl.** **09-01**

(52) **U.S. Cl.**

USPC **D9/547**

(58) **Field of Classification Search**

USPC D9/516, 547, 560; D7/589, 601, 602,
D7/615

See application file for complete search history.

(57) **CLAIM**

The ornamental design for a glass storage jar as shown and described.

DESCRIPTION

FIG. 1 is a perspective view of a glass storage jar showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a top plan view of a glass storage jar in open position of the lid.

Broken lines in the drawings depict portions of the glass storage jar that form no part of the claimed design.

1 Claim, 8 Drawing Sheets
